FRAME FOR HANDBAGS AND THE LIKE

Willi Hammesfahr, Solingen-Wald, Germany, assignor to John G. Treacy, New York, N. Y.

Application January 10, 1952, Serial No. 265,796

1 Claim. (Cl. 150—29)

1. The present invention relates to frames for bags and in particular for ladies' handbags.

Frames for bags are known in which spring metal plates have been provided which bring about a self-locking of the bag by means of the said spring metal plates. The latter also serve in this case as locking means for the open position of the bag. In order to achieve this locking position, the pivots connecting the said spring metal plates are provided with notches which maintain the open position of the bag, and a slight pressure is required to bring about the closed position of the bag. The spring metal plates move during the opening and closing, respectively, of the bag, in a plane from each other and towards each other, respectively, and accordingly the pivots are disposed perpendicularly to the said plane.

It is one object to provide pivot means which not only permit a locked closed and open position, respectively, of the bag in connection with the spring metal plates, but also with bags comprising two U-shaped members which are pivoted to each other.

It is another object of the present invention to provide the ends of one of two U-shaped members, forming the frame of a bag, with a cam member, while each end of the other U-shaped member carries a part which engages the cam.

It is still another object of the present invention to provide a frame for handbags which comprises two U-shaped members which are hinged to each other, and the ends of one of the U-shaped members being formed in the shape of an angle, the free arm of which is formed to a cam, which engages a part carried by each end of the other U-shaped member.

It is yet another object of the present invention to provide a frame for a bag which comprises two U-shaped members hinged to each other, the ends of one of the U-shaped members being formed to cams, while balls mounted in the ends of the other U-shaped member engage the mentioned cams.

It is a further object of the present invention to provide a frame for handbags which comprises two U-shaped members shaped from hollow rods of any suitable cross-section, the ends of one of the U-shaped members being connected to sleeves formed to a cam member, while the ends of the other U-shaped member are connected with sleeves receiving a helical coil spring which presses a ball to engagement with the corresponding cam.

With these and other objects in view which

will become apparent in the following detailed description, the present invention will be clearly understood in connection with the accompanying drawing, in which:

Figure 1 shows a side view of the frame for a handbag, the latter indicated in dotted lines, in closed position;

Fig. 2 is an end view thereof;

Fig. 3 is an end view thereof, however, in open position;

Fig. 4 is an end view, partly in section, of the joint of the frame; and

Fig. 5 is a section along the lines 5—5 of Fig. 4.

Referring now to the drawing, the frame comprises two preferably substantially U-shaped members 1 and 2 which are disposed parallel to each other in the closed position of the bag and are preferably of hollow, i. e. tubular, material or the like. The U-shaped members 1 and 2 have comparatively long arms 4 and 5, respectively, and the ends of the arms 4 are hinged to the corresponding ends of the arms 5.

The arm ends 4 of the U-shaped member 1 form to a cam disc 6 which is equipped with notches 7 and 8. The cam disc 6 is equipped with an opening 12 which receives the pivot 13. The latter is mounted in the joint 14 of the arms 5 of the U-shaped member 2 and thus forms the pivoting axis for the U-shaped member 2.

An engaging member 9 is mounted in each free end of the arms 5 of the U-shaped member 2, which engaging member 9 is preferably formed as a ball and, by means of a helical coil spring 11 disposed in a sleeve 10, is pressed towards the notches 7 and 8 of the cam 6 in the closed and open position, respectively, of the bag. A steep incline on the cam 6 leads to the notch 7 in order to secure the engagement of the two U-shaped members 1 and 2 in the closed position of the bag.

The cam 6 may be formed as one arm of an L-shaped member 15, the other arm 16 of which is secured to the free end of the arms 4 of the U-shaped member 1.

As shown in Figs. 4 and 5, the joint for the bag frame may be designed as independent structure to be inserted into the free ends of the arms 4 and 5, respectively, of the members 1 and 2. In this case, the sleeve 10 receiving the coil spring 11 and ball 9 and the angle arm 16 may be inserted into the ends of the tubular arms 4 and 5, respectively. The operation of the present joint is performed in the following manner:

Upon opening of the frame the ball 9 will be lifted from engagement with the notch 7 of the cam 6 into the sleeve 10, at the same time com-

pressing the spring 11. The ball 9 slides along the outer periphery of the cam 6 until such time as the ball enters the notch 8 which is clearly felt as the limit of the opening movement.

In order to close the bag it is merely necessary to lift the ball 9 from the notch 8 and to slide the ball 9 along the periphery of the cam 6 until the ball 9 snaps into the notch 7, bringing about the closed position of the bag and a secure locking of the members 1 and 2 in the closed position.

While I have disclosed one embodiment of the present invention, it is to be understood that this embodiment is given by example only and not in a limiting sense, the scope of the invention being determined by the objects and the claim.

I claim:

A hinge in a frame for a handbag comprising a pair of substantially U-shaped frame members, each of the said frame members consisting of a base portion and two leg portions extending from the respective ends of the said base portion, the said U-shaped frame members being disposed in adjacent parallel arrangement in the closed position of the said handbag and in angular arrangement upon an axis formed by the connecting line between the free end parts of the said leg portions of each of the said U-shaped frame members, the respective bases of the latter being spaced apart from each other, in the open position of the said handbag, at least the free end parts of the said leg portions being tubular, a pair of L-shaped cross members of flat material, one arm of each of the said L-shaped cross members being secured to the free end parts of the legs of one of the said U-shaped members, respectively, each of the free end parts of the legs of the other of the said U-shaped frame members having an open axially disposed slot receiving therein the other arm of one of the said cross members which is secured to the adjacent leg of the other of the said U-shaped members, respectively, a pivot extending through the free end parts of the legs of the other of the said

U-shaped frame members and through the said other arm of the said cross members, thereby pivotally connecting the free end part of the legs of one of the said U-shaped frame members with the free end part of the legs of the other of the said U-shaped members, the free end of the said other arm of the said cross members forming a cam having two notches spaced apart from each other over a center portion, a contacting member comprising a ball disposed in the free end part of each of the legs of the other of the said U-shaped frame members and engaging the corresponding one of the said cams, and resilient means comprising a helical spring disposed in the free end part of each of the legs of the other of the said U-shaped frame members urging the said contacting member toward the said cam, thereby retaining the said U-shaped frame members in parallel closing position of the bag, when the said contacting members engage one of the said notches of the said cams and in angular opening position of the bag, when the said contacting members engage the other of the said notches of the said cams.

WILLI HAMMESFAHR.
